[57] CLAIM

The ornamental design for a multipurpose wall-mountable caddy, as shown.

DESCRIPTION

FIG. 1 is a top, front, and left side perspective view of a multipurpose wall-mountable caddy showing my new design, the broken-line depiction of suction-cup mounting means being for illustrative purposes only and forming no part of the claimed design;

FIG. 2 is a top plan view thereof;

FIG. 3 is a front elevational view thereof;

FIG. 4 is a right side elevational view thereof;

FIG. 5 is a rear elevational view thereof; and

FIG. 6 is a bottom plan view thereof.

FIG. 1

FIG. 2

FIG. 3

FIG. 4

FIG. 5

FIG. 6
